[57] ABSTRACT

An apparatus is disclosed for applying bundle ties to bundles, the bundle ties being of the type comprising an elongated thin strip of plastic material having an opening in its trailing end so that the leading end of the tie can be inserted through the opening and the tie drawn up into snugly embracing relationship with the bundle. The apparatus comprises a means for feeding the bundle ties, leading end first, along a path extending around the bundle and through the opening in the trailing end of the tie. After the leading end is threaded through the opening, the end of the tie is grasped and pulled away from the bundle while the trailing end is pressed towards and against the bundle. A cutoff device, which is responsive to the development in a predetermined tension in the tie, is then operated to cut the excess portion of the strap which extends beyond the trailing end of the tie.

APPARATUS FOR APPLYING TIES TO BUNDLES

BACKGROUND OF THE INVENTION

It is now common practice to use plastic bundle tie devices for bundling wires in electrical harnesses and under other circumstances where a large number of wires extend parallel to, and beside, each other. The most popular general type of tie being used comprises an elongated molded strip of plastic having a laterally extending head on its trailing end in which there is provided an opening. In use, the tie is simply wrapped around the bundle of wires and the leading end is inserted through the opening. The tie is then drawn up snugly and the excess portion of the strap, which extends beyond the head, is cut off. The head has tooth or ratchet means of some sort therein which prevents reverse movement of the strap portion through the head so that the tie remains in place.

Ties of the general type described above can be applied by hand if desired but where a large number of ties are applied by a single operator, it is common to use one of the commonly available hand tools as disclosed, for example, in U.S. Pat. No. Re. 26,492. These commonly used tools are of the pistol grip type and are arranged such that when the handles are squeezed, the leading end of the tie will be drawn through the opening in the head and the preferred forms of hand tools have an automatic cutoff feature which cuts and excess tie at the head after the tie has been snugly drawn onto the bundle.

It has been recognized that a fully automatic apparatus for applying tie devices to wire bundles would be useful under many circumstances, for example, where harnesses are being mass produced and hundreds of ties are being applied by a single operator during a working shift. Manual application of the ties to a bundle is relatively slow and somewhat uncertain in view of the fact that the tie is only drawn up as snugly as the operator feels inclined to draw it up and the inevitable effect of operator fatigue is that the operator tends to apply the ties only relatively loosely to the bundles. The presently available hand tools overcome this problem in that the tie is always drawn up to a predetermined degree of tension on the bundle and there is some mechanical advantage to these hand tools although they still require substantial manual effort, particularly where large number of ties are being applied. Furthermore, the application rate is relatively low for hand tool tie applying devices, hardly better than the application rates achieved by manual application.

The present invention is specifically directed to the achievement of a fully automatic tie applying apparatus which will offer all of the advantages of presently available hand tools and which additionally will substantially increase the speed of application of the bundle ties to a bundle. The invention is moreover directed to the achievement of the tool which will be relatively compact and light in weight so that it can be held by an operator for prolonged periods and without undue fatigue.

It is accordingly an object of the invention to provide an improved apparatus for applying bundle tie devices to bundles of wires or the like. A further object is to provide a semi or fully automatic tie applicator which can be applied to bundles of any size within the limitations of the tie itself. A further object is to provide a bundle tie applicator which is capable of applying a

bundle tie to a bundle in an extremely short time interval, substantially less than that required for manual or hand tool application. A still further object is to provide an apparatus which is thoroughly reliable and which can be operated with a minimum amount of skill on the part of the operator.

These and other objects of the invention are achieved in a preferred embodiment thereof which is briefly described in the foregoing abstract, which is described in detail below, and which is shown in the accompanying drawings in which:

FIG. 1 is a perspective view of a preferred form of bundle tie applicator in accordance with the invention.

FIG. 2 is a perspective view of a typical bundle tie device.

FIG. 3 is a perspective view of a bundle tie device applied to a bundle of wires.

FIGS. 8-7 are diagrammatic views illustrating the steps in applying the bundle tie device of the FIG. 2 to a bundle of wires, these views illustrating the operations performed on the bundle tie device during the operation of the applicator of the instant invention.

FIG. 8A-8D are perspective views showing the frame and cover plate members of the apparatus of FIG. 1.

FIG. 8E is a perspective view showing some of the principle moving parts of the apparatus of FIG. 1.

FIG. 9A is a fragmentary longitudinal section view of the apparatus of FIG. 1, this view being taken along a section which shows the main actuator slide and the piston-cylinder for this main slide.

FIG. 9B is a diagrammatic view similar to FIG. 9A showing the positions of the main slide, the auxiliary slide, and the piston and gear wheel at the beginning of the return stroke of the piston.

FIG. 9C is a view similar to FIG. 9B but showing the positions of the parts immediately before the excess strap portion of the main tie is cut by the cutting means.

FIG. 9D is a view similar to FIG. 9C but showing the positions of the parts at the instant of the cutting of the cable.

FIG. 10 is a front view of the apparatus, with parts broken away, showing the positions of the parts prior to the commencement of an operating cycle.

FIG. 11 is a view similar to FIG. 10 but with some parts of the cover plate broken away and illustrating the positions of the parts after the bundle tie has been wrapped around the bundle and its leading end has been threaded into the opening in the head of the bundle tie device.

FIG. 12 is a fragmentary view, on an enlarged scale, of the bundle tie application zone of the apparatus, this view illustrating the positions of the parts immediately after threading of the leading end through the opening in the trailing end of the bundle tie device.

FIG. 13 is a view similar to FIG. 12 but showing the positions of the parts at a later stage in the operating cycle and immediately prior to drawing up or tensioning the bundle tie device on the bundles.

FIG. 14 is a fragmentary sectional view illustrating the positions of the parts after the bundle tie has been drawn into snugly embracing relationship with the bundle and the excess strap portion of the tie has been cut adjacent to the head of the tie.

FIG. 15 is a fragmentary view illustrating the actuation of the closeable guide which functions to guide the leading end of the bundle tie device around the bundle of wires.

FIGS. 16 and 17 are views taken along the lines 16—16 and 17—17 of FIG. 10.

FIG. 18 is a view taken along the lines 18—18 of FIG. 11.

FIG. 19 is a fragmentary perspective view showing the elements of the lower cutter of the apparatus and the actuating means for actuating this cutter to cut the tie device after tensioning.

FIG. 20A is a fragmentary view showing features of a guiding device which guides the leading end of the bundle tie into a reciprocable head on the main slide.

FIG. 20B is a view similar to FIG. 20A but showing the manner in which this guide device is disengaged from the leading end of the bundle tie.

FIGS. 21A—21D are a series of sectional side views illustrating the operation of a mechanism for reorienting the fixed cutting blade means of the apparatus so that this cutting blade is located in opposition to the movable cutting blade.

FIG. 21 E is a view taken along the lines 21E—21E of FIG. 21A.

FIG. 22 is a fragmentary view which shows an operating slide for actuating a locking pin mechanism which is shown in FIG. 23.

FIG. 23 is a sectional view illustrating a locking pin for locking the fixed cutter in its operative position relative to the movable cutter.

FIG. 24 is a fragmentary view showing features of the mechanism of FIG. 22.

FIG. 25 is a perspective exploded view of the tie pushing and gripping head which is mounted on the main slide of the apparatus.

FIG. 26 is a sectional side view of the gripping head of FIG. 25, showing the positions of the parts when the leading end of the tie is gripped therein.

FIG. 27 is a Figure similar to FIG. 26 but illustrating the manner of releasing a cut section of tie from the gripping head.

FIG. 28 is a sectional transverse view illustrating features of the mechanism for driving the movable cutter towards the fixed cutter.

FIGS. 29 and 30 illustrate the details of the mechanism of FIG. 28.

FIGS. 31A and B are a timing diagram which set forth the sequence in which the various parts are actuated.

Referring first to FIGS. 1—3, a preferred form of apparatus 16 in accordance with the invention is adapted to apply individual bundle ties 2 to wire bundles 4. Each tie comprises an elongated relatively narrow strap portion 6 having a tapered and pointed leading end 8 and having a trailing end 10. A laterally extending head 12 is provided on the trailing end and an opening extends therethrough normally of the plane of the strip 6. Suitable detent means such as teeth 14 are provided in the opening so that the strap cannot be retracted from the opening after it has been inserted therethrough from the underside.

When a bundle tie 2 is manually applied to a bundle 4, the strap portion 6 is simply passed around the bundle, the leading end 8 is inserted through the opening in the head 12, and the tie is drawn up snugly onto the bundle. In the operation of the instant apparatus, the tie is manipulated in a very precise manner as illustrated in FIGS. 4—7. An understanding of the movements of the tie during application as illustrated in

FIGS. 4—7 will be helpful to an understanding of the specific details of the apparatus as presented below.

As shown in FIG. 4, the apparatus first aligns the bundle tie beside the bundle 4 with the leading end 8 directed transversely of, and spaced from, the surface of the bundle. The tie is then fed leftwardly and the leading end 8 is guided around the bundle then upwardly until the leading end enters the opening in the head 12. It should be noticed in FIG. 5 that the portion 7 of the strap adjacent to the leading end extends substantially straight towards the head and is not curved as are the other intermediate portions of the tie. Subsequently, the head is moved leftwardly along a straight line path towards the upper side of the bundle as shown in FIG. 6 and a leftwardly directed force is applied to the portion 7 of the tie on the lefthand side of the bundle as viewed in this Figure. As a result, the portion 7 of the tie is forced to move relatively upwardly through the opening in the tie. The axis of the opening in the head portion 12 of the tie now extends substantially tangentially of the righthand side of the bundle. Thereafter (FIG. 6A) the head is reoriented so that the opening in the head 12 is substantially radially oriented so that the axis of the opening extends radially towards the center of the bundle of wires. Finally (FIG. 7) the leading end is drawn rightwardly until the tie snugly embraces the bundle and the tie is cut as shown adjacent to the head portion 12.

Apparatus 16 comprises generally a body portion having a tie applying zone 18 on the lefthand end thereof as viewed in FIG. 1 and a tie magazine 20 on its upper side which holds a supply of individual bundle tie devices 2 for application to wire bundles. The body portion 16 comprises (FIGS. 8A—8D) a static support and frame means including a front cover plate 28, a front side frame plate 24, a main frame plate 22, and a rear side frame plate 26, these parts being assembled against each other in the order named. These four support and frame members have numerous pockets openings, and slots therein which will be identified as this description proceeds when their significance is discussed. Some of the principle dynamic and kinematic elements of the apparatus are shown in FIG. 8E and comprise a piston-cylinder 50 having a piston rod 56 extending rearwardly therefrom which has a gear wheel 60 on its end. This gear drives a main slide 42 towards and away from the tie applying zone 18 and transmits forces to most of the individual mechanisms which will be described in detail below. For example, the main slide 42 has mounted on its leading end a slide head 34 (FIGS. 25—27) which functions to push the tie along a circular path around the bundle and later to grip the leading end of the tie and pull it through the opening in the tie head until the tie is drawn snugly around the bundle. This main slide also actuates a guide closing means (FIG. 15) which closes the tie guide in the tie application zone 18. The cutoff mechanism, (FIG. 14) which severs the excess tie strap material at the end of the tensioning operation, is actuated at the end of the operating cycle by an additional slide 64.

To begin now a detailed description of the embodiment of the invention, a tie device is fed laterally into an opening 30 of the front side plate 24 and positioned on a knife edge 32 which defines the lower edge of opening 30. The tie is thus located with its leading end pointed leftwardly as viewed in the drawing and with its head portion adjacent to the righthand end of the knife

edge 32. Advantageously, a small stop block 33 is mounted on the right-hand end of the knife edge to prevent movement of the tie device beyond the knife edge. A small piano wire spring 35 is provided in this stop block to prevent the tie from falling forwardly in the event that the apparatus should be tilted upwardly.

The tie 2 is fed by a slide head 34 (FIGS. 25-27) comprising a slide head block 36 having a vertical recess 38 in its forward end. Immediately below this recess there is provided a forwardly facing tie pushing surface 40 which moves over the knife edge 32 and which engages the head 12 of the tie device to push it along a circular path defined by a guiding means which is described below. The main slide 42, to which the slide head 34 is secured, is supported on the upper surface 44 of the frame plate 22. An elevated section 46 is provided on the frame plate adjacent to the righthand end thereof and a channel 48 is provided in this elevated section for the accomodation of the portion of the slide 42. The slide is actuated by a piston cylinder 50, (FIG. 9) which is supported in openings 52, 54 in the frame plate sections 22, 26. This piston cylinder has a rightwardly extending piston rod 56 having a yoke 58 on its end in which a gear wheel 60 is supported. This gear wheel extends upwardly through an opening 61 in the frame section 22, so that the teeth 62 on the under side of the frame slide will mesh with the gear wheel. The gear 60 also meshes with a secondary or auxiliary slide 64 in the lower portion of the apparatus. As will be explained below, this secondary or auxiliary slide 64 is moved rightwardly only during the final portion of the operating cycle to actuate the tie cutoff device. For purposes of the present discussion, it can be assumed that this secondary slide 64 is stationary.

The actuation of the main slide 42 is as follows: At the beginning of the operating cycle, the parts are in the position of FIG. 9 with the piston rod 56 extended from the cylinder 50 to the rightward limit of its stroke and with the main frame slide 42 in its retracted (i.e. starting) position. As compressed air is admitted into the righthand end of the cylinder, the piston rod 56 is moved leftwardly, its teeth meshing with the teeth of the auxiliary slide 64 which remains stationary as mentioned above. The main slide 42 is moved leftwardly at a velocity which is twice that of the velocity of the piston rod by virtue of the fact that the teeth of the gear pull the slide leftwardly and at the same time the gear rotates in a counterclockwise direction because of the fact that it must roll over the stationary rack bar 64. The rotation of gear 60 drives the slide leftwardly independently of the direct pull imparted to the slide by the piston rod. The stroke of the main slide is therefore, twice the stroke of the piston rod 56.

The tie device is pushed leftwardly as viewed in the drawing and then along circular paths so it surrounds the bundle of wires positioned in the application or tie applying zone of the apparatus. A guide means for the leading end of the tie is supported in arcuate recesses 68, 66 in the plate members 24, 28 and comprises an arcuate guide member 70 disposed between these plates and having a pin 74 which extends into the arcuate slots 72 in the plates which are adjacent to the arcuate edges of the recesses. The arcuate guide member is thus slidable along a circular path from the position shown in FIG. 10 to the position shown in FIG. 11 in which it defines a circular path for the tie device.

Referring now to FIGS. 10 and 15, the movement of the guide member 70 is achieved by means of a arcuate link 76 which is pivoted to the pin 74 which extends into the recess in the plate member and which is also pivoted at 78 to a crank arm 80. The crank arm 80 in turn, is fixed to the end of a short shaft 82. A generally triangular plate 84 is secured to the arcuate link 76 along the base portion of the plate and has its apex pivoted at 86 to an arm 88 which comprises a dummy crank which is identical to the previously identified crank 80. Crank 88 is provided in order to ensure that the crank 80 will move over center from the position of FIG. 10 to the position of FIG. 15 and causes the guide member to move from its open position to its closed position.

The arm 88 is pivoted at 90 to a forwardly extending bracket 92 which in turn is secured to the cover plate 28. A spring 94 is provided to take up the free play in the arm 88 and to assist the guide closing and opening operations. This spring is anchored at one end 95 to the plate 28 and has its other end secured to a pin 98 on the crank 88. The pin is received in an arcuate slot 100 of the bracket 92 which slot has the pivotal axis 90 as a center so as to limit the movement of the arm 88 between the two extreme positions shown in FIG. 10 and 15.

The linkage described above is actuated by a reciprocal slide 106 which is guided in a slot 108 on the plate member 24 and which has a rack bar 104 on its lefthand end. The teeth of the rack bar mesh with the teeth of a gear 102 on the shaft 82 to which the arm 80 is fixed. Reciprocation of the slide 106 between the extreme positions shown on FIGS. 10 and 15 will thus result in shifting of the linkage between the two positions shown in these FIGS. and closing of the guide member 70.

The slide member 106 is reciprocated by the downwardly extending arm 112 of a bell crank 114 to which the slide 106 is pivoted at 110. The bell crank 114 is pivoted at 116 to a bracket 118 secured to the frame member and has a shrot horizontally extending arm 120 on the end of which there is provided a roller for engagement with a cam 124 on the underside of the main slide 42. It will be apparent that upon leftward movement of the main slide, the cam 124 will move leftwardly from the position shown in FIG. 10 and the forward surface 126 of the cam will cause the bell crank 114 to swing through a clockwise arc about its pivotal axis 116. During this movement of the bell crank, the arm 112 drives the slide member 106 leftwardly to close the guide 70 into surrounding relationship to a bundle of wires which are located in the application zone. Another bell crank 128 is pivotally mounted on a pivot pin 130 which is mounted in the frame member. Bell crank 128 has a leftwardly extending arm 132 and a depending arm 136. The arm 132 has a roller on its end for engagement with the rightwardly facing side 134 of the cam block 124 and the depending arm is connected by a link 130 to the arm 112 of the bell crank 114.

When the main slide and the cam 124 move leftwardly and the bell crank 114 is swung through a clockwise arc, the bell crank 128 is also swung through a clockwise arc by the link 138 so that the arm 132 is in a horizontal altitude as shown in FIG. 15. During the return stroke of the main slide, the cam surface 134 will cause counterclockwise movement of bell crank 128

which in turn will swing the arm 112 through a counter-clockwise arc and move the slide 106 rightwardly to open the guide member 70.

As is apparent from the timing diagram, the guide 70 is closed during the initial portion of the stroke of the main slide 42 so that the guide will be closed by the time the leading end of the tie device reaches the left-hand portion of the frame and the tie device will then be guided along the circular path as illustrated in FIGS. 11 and 12 to surrounding relationship with the bundle. The guide remains closed during most of the operating cycle and is opened during the final portions of the return stroke.

Referring now to FIG. 22, it is desirable to latch the guide 70 in its closed position during feeding of the tie device into surrounding relationship with the bundle. The guide 70 is latched in its closed position by means of a guide latch 71 which is pivoted at 73 between two ears which extend from the frame plates and this latch member has a tooth 83 which extends into a complementary notch in the guide 70 as shown. Latch 71 is biased in a clockwise direction as viewed in FIG. 22 by a spring 85 which is interposed between an ear which is integral with the frame and the end of the arm. The latch also has an upwardly extending arm 75 which is engaged by a latch release lever 77.

It will be apparent that as the guide member 70 moves along an arcuate path, past the latch, it will cam the latch member in a counterclockwise direction until the tooth 83 falls into the notch in the guide member and the latch will be maintained in engagement with the guide member by the spring 85. The latch is disengaged that is, swung along a counterclockwise path from the position shown in FIG. 22, by means of a latch release lever 77. This lever is pivoted to and depends from the end of a slide 79 which in turn is connected by a pin 81 to a slide member 312. The slide member 312 is moved rightwardly from a position shown in FIG. 22 for a short distance after feeding of the tie has been completed. During this rightward movement of slide 312, lever 77 is caused to move through a clockwise arc when its upper portion engages the frame and the lever swings the arm 75 through a slight counterclockwise arc thereby disengaging the latch member. The actuation of slide 312 is described below.

The path along which the tie is fed during the forward stroke of the main slide extends over the upper surface 140 of an upwardly extending ear 144 of a slide plate 142 (FIG. 19) which is contained between the cover plate 28 and the side plate 24. The feed path extends past an upper or fixed cutter means 148, (FIG. 11) along the inner surface of the arcuate guide member 70, along an arcuate guide surface 152 of the slide 142, thence along a vertical surface 160 on the leading end of the slide 142 and into the slide head 34. It is desirable to ensure accurate guidance of the relatively thin tapered leading end 8 of the tie into the slide head 34 and to achieve such guidance, a guide finger 146 is pivotally mounted on a vertical axis on the outwardly facing side of the ear 144 of slide plate 142. Finger 146 has an inwardly directed end 162 which is spaced from the surface 160 so that a confined opening is presented for the leading end 8 of the tie. The finger 146 is normally biased in a clockwise direction as viewed in FIG. 20A by a spring 168 which is interposed between the trailing end of a finger and a fixed bracket 174 on the opposite side of the ear 144. It should be added at this point that

the upper corner 169 of the inwardly directed portion 162 of finger 146 provides a rounded surface over which the tie is drawn during the return stroke of the slide head as is best shown in FIG. 14.

It is necessary to pivot the finger 146 in a counterclockwise direction as viewed in FIG. 20A in order to permit the head 12 of the tie to move towards the wire bundle as illustrated in FIGS. 6 and 6A. To bring about this pivotal movement of finger 146, a roller is provided on a depending pin 163 on the underside of the finger. This roller is adapted to be engaged by a fixed cam 165 on the internal surface of the cover plate 28 during forward movement of the main slide 42 to swing the finger in a counterclockwise direction as shown in FIG. 20B. It is advantageous to provide an additional cam 167 on the surface of cover plate 28 which engages the finger 146 during the return stroke of the slide to ensure that the finger will be returned to its normal position for the next operating cycle.

The block 150 provides a transition surface between the end of the arcuate guide 70 and the surface 152 of the slide plate 142 and is normally disposed in a recess 154 in the leading edge of slide plate and biased leftwardly as viewed in the drawings by a spring 156. This block 150 is thus permitted to move relatively into the recess 154 during the leftward movement of the slide plate 142 as is described below.

When the parts are in the position of FIG. 11 and the leading end 8 of the tie had been fed to the upper end 30 of ear 144 of the slide plate 142 and up to the opening in the head 12 of the tie, it is then necessary to move the slide plate 142 leftwardly while feeding of the tie continues (i.e. while the leftward movement of the head 34 and the main slide 42 continues) in order to force the leading end of the tie to move relatively through the opening in the head 12 of the tie and into the gripping means in the slide head 34. Normally, the slide plate 142 is biased rightwardly by a spring 176 which is disposed in a slot 180 in the slide plate 142 and which bears against the righthand end of the slot and against a fixed block 177 which is mounted on the frame plate 24. An additional biasing force is provided by a spring 182 which is interposed between a depending portion 184 of the slide plate 142 and a block 186 which is beneath the previously identified guide block 150 and is secured to frame plate 24. The slide plate 142 is moved leftwardly against the biasing force of the springs 176, 182 by the main slide which engages an upwardly extending arm 172 (FIG. 19) of a plate 174 which is fastened to the reverse side of slide plate 142.

The short leftward stroke of the slide 142, during which it moves from the position of FIG. 11 to the position of FIG. 12, causes the leading end of the tie and a portion 7 of the tie which is adjacent to the leading end to be advanced through the opening in the head of the tie. The head 12 of the tie is moved leftwardly during this portion of the operating cycle but at the same time, the portion of the tie which is against the surfaces 160, 152 of the slide 142 are also moved leftwardly and because of the fact that the tie is confined completely around its circumference, the leading end 8 is forced to feed itself through the head and into the slide head 34 where it is gripped in a manner described immediately below.

Referring now to FIGS. 25-27, the leading end of the tie is gripped between a locking pawl 188 pivotally mounted in the recess 38 in the forward end of the slide

head block 36 and a clamping block 194 which is normally spaced from the leading end of the slide head block. The pawl 188 is resiliently biased in a counter-clockwise direction as shown in FIG. 26 by a spring 190 and a tooth on this pawl moves between two adjacent teeth on the leading end 8 of the tie so that the tie is securely held against the surface 192 of blade 194 and is securely held when the parts are in the positions of FIG. 26. The clamping block 194 has two rearwardly extending arms 196 which are received in recesses 198 on the outwardly facing sides of the block 36 and which are secured at their rearward ends by a pin 202 to a block 200 which is disposed in a recess 204 in the rearward end of the block 36. A rod 206 is mounted in the block 200 and extends forwardly through the recess 204 in the block 36 and into drilled hole 210 and a spring surrounds this rod and is effective between the leftwardly facing surface of block 200 and the inner surface of the hole 210 so that the slide block 200 is biased rightwardly to the position shown. It will be apparent that the spring 208 provides a clamping pressure on the leading end of the tie in that it biases the clamping block 194 rightwardly and towards the pawl 188.

The tie is released by moving the slide head block 36 rightwardly relative to the clamping block 194 and this is accomplished by means of a cam 232 in cooperation with a latch arm 212. The latch arm 212 extends through a channel 220 on the upper surface of block 36 and is bifurcated at its leading end 222. The leading end also has a pair of spaced apart depending fingers 224 which are received in pockets 226 on opposite sides of the clamping block 194. These fingers are pivoted to the block 194 by means of a pin 228, springs 230 being provided between the lower ends of the fingers and the block to bias the latch arm 212 in a clockwise direction as viewed in FIG. 26. The righthand end of the latch arm 212 has a pair of spaced apart depending hooks or hook-like portions 214 which lodge against the rightwardly facing surface of the inner end recess 204 and a roller 216 is mounted on a pivot pin between these hook-like portions. This roller is in alignment with a relatively narrow slot 218 on the upper surface of the block. The previously identified cam finger 232 extends from a mounting block 234 which is secured to the frame member 24 as shown. It will be apparent from FIGS. 26 and 27 that at the end of the return stroke of the main slide, the slide head will move into engagement with the cam finger 232 which engages the roller 216 causing the latch arm 212 to pivot upwardly out of engagement with the block 36. As the slide block 36 continues its rightward movement, the clamping block 194 remains stationary so that the leading end of the tie is released. The leading end is released after the excess tie material has been cut at the tie head as will be described below.

During the initial portion of the return stroke of the main slide 42, the head of the tie is moved along an arcuate path from the position it occupies in FIG. 12 towards the bundle of wires. After this movement of the head 12, it is oriented such that the axis of the opening in the head extends substantially radially with respect to the bundle as shown in FIG. 13. The head of the tie is moved from the position of FIG. 12 to the position of FIG. 13 by means of the fixed cutter which is moved during this interval into its operative position for the operations of drawing the tie tightly and snugly around

the bundle and for the subsequent cutting of the excess tie material as will subsequently be described.

As shown best in FIGS. 12 and 13, the fixed cutter means comprises an upper toggle link 238 which is pivoted at 240 to the main frame and which is pivoted at its lower end 242 to a lower toggle link 244. This lower toggle link is pivoted intermediate its ends at 246 to the frame plate 24 and has a recess 248 on its end which conforms to the contours of the upwardly facing surface of the head 12 of the tie. When the toggle is straightened (FIG. 13), the head of the tie is thus moved along the arcuate path described above, and the cutting edge which is the toggle link 244 is positioned for cooperation with the movable cutter as will be described below. The toggle is straightened by means of an actuator pin 250 which moves in an arcuate slot 251 in a counterclockwise direction with reference to the pivot point 240 of the toggle link 238.

The mechanism for moving the actuator pin 250 along an arcuate path from the position of FIG. 12 to the position of FIG. 13 is shown in FIGS. 21A-21D and comprises a bell crank 254 having a depending arm 256 in which the actuator pin 250 is mounted. Bell crank 254 is mounted on a pivot pin 240 in a housing 252 and has a horizontally extending arm 260 on the end of which a roller 262 is provided. This roller is engaged by a cam 264, when the cam is moved rightwardly from a forward position as shown in FIGS. 21C and 21D, to swing the bell crank 254 through a counterclockwise arc and move the actuator pin 250 along a similar arc. Cam 264 is normally disposed to the right of the bell crank 254 (FIG. 21A) and must be lowered during the final forward stroke of the main slide and moved to a position to the left at the roller 262 before the return stroke of the ram or slide. The structure which is described below thus functions to move the cam 264 from the position of FIG. 21A forwardly and downwardly (FIG. 21B) so that it is enabled to clear the roller 260. During the return stroke then, the cam effectively swings the bell crank through the counterclockwise arc shown in FIG. 21D.

The mechanism from moving the cam along the path described above comprises a cam slide 266 contained in the housing 252 and having a depending portion 268 which is normally against an upstanding ear 270 of the frame member 24. The slide is biased rightwardly as viewed in FIG. 21A by means of a spring 272 which bears against a cover plate 274 of the housing and extends into a drilled opening in the depending portion 268 of the slide. The slide is moved leftwardly to the position of FIG. 21C during the final portion of the forward stroke of the main slide 42 by means of an arm 276 which is mounted in a recess 278 on the leading end of slide 42. The free end of arm 276 has a notch 282 therein which is adapted to receive a depending tooth 284 of the portion 268 of the slide, the arm 276 being biased in a clockwise direction as viewed in FIG. 21A by a light spring 280. As the main slide 42 moves from the position of FIG. 21A to the position of FIG. 21B, the arm 276 is swung through a slight counterclockwise arc until the tooth 284 is disposed in the recess 282. Thereafter, and upon further forward motion of the main slide, the cam slide 266 moves to its extreme forward position. It should be mentioned at this point that the tooth 284 and the notch 282 are provided in order to ensure return of the cam slide 266 to its starting position. The arm is disengaged from the

tooth 284 by virtue of the impact of the depending portion portion 268 of the cam slide against the rib 270 of the main frame member 24.

The cam 264 is on the end of a thin plate-like arm 286 which is contained in a recess in the cam slide 266 and is pivoted to the cam slide as shown at 288 adjacent adjacent to its righthand end. A light biasing spring 290 it interposed between a suitable shoulder in the cam slide 266 and a radially extending shoulder on the end of the arm to bias the arm 286 in a clockwise direction. Intermediate its ends, the arm 286 has a roller 292 thereon, which engages an inclined surface 300 of a block 294 which is pivoted at 296 in a recess extending downwardly from the upper surface of the housing. The block 294 is biased in a clockwise direction to the position shown in FIG. 21A by means of a spring 298 which extends between a pin fixed to the housing and a pin extending from the block 194.

As the cam slide 266 moves leftwardly from the position of FIG. 21A to the position of FIG. 21B, the roller 292 is forced to move relatively downwardly and forwardly over the surface 300 and then over the surface 302 of a slide block 304 which is also contained in the housing 252. This slide block is biased rightwardly by a spring 305 and yields to some extent as shown in FIG. 21B so that when a sufficient gap opens between the corner of this slide block and the adjacent corner of the block 294, the arm 286 returns to its horizontal altitude and the roller 292 moves obliquely upwardly until it reaches the position of FIG. 21C and the slide block 304 is permitted to return to its normal position. The cam 264, during this portion of the cycle, has been lowered and moved forwardly until it is beyond the roller 262 on the bell crank arm 260 so that at the very end of the stroke of the main slide 42, the inclined surface of the cam 264 is to the left of the roller 262. When the main slide 42 moves rightwardly as viewed in FIG. 21A-21D, the cam then moves against the roller and causes the bell crank 254 to swing through the arc shown. The roller 292 is permitted to return to its original position (FIG. 21A) by virtue of the fact that it moves the block 294 through a slight counterclockwise arc (FIG. 21D) against the biasing force of the spring 298.

The toggle linkage 238, 244 of the fixed cutter is straightened by the actuator pin 250 as described above but the mechanism for straightening this toggle linkage shown in FIGS. 21A-21D is effective during only a brief interval encompassing the end of the forward stroke of the main slide. The bell crank 254 is returned to its normal position (FIG. 21A) after the toggle linkage is straightened by a spring 255 which extends between the arm 260 of the bell crank and the frame. It is therefore necessary to lock this toggle linkage in its straightened position of FIG. 13 during the remainder of the return stroke of the main slide and this is accomplished by a locking pin 308 shown in FIGS. 22 and 23, which enters a hole in the link 244 as shown in FIG. 13.

The locking pin and its actuating means are contained in a housing 310 and the pin is controlled by an actuator or control slide 312 which has a laterally extending pin 314 that extends through an opening in side plate 28 and is fixed in a slide member 324. The locking pin 308 is mounted on an arm 316 which extends beside, and is spaced from, the side plate 28 and which is pivoted at 318 to the housing 310. A spring 320 biases

the arm 316 in a clockwise direction as viewed in FIG. 23 so that it would normally be in engagement with the toggle link and extend beyond the plate 28. The arm 316 is held in the position of FIG. 23 during most of the forward stroke of the main slide by means of the previously identified slide 324 which has an inclined surface 326 on its lefthand end in engagement with roller 322 mounted on the arm 316 intermediate the ends thereof. Also, a helper spring 328 is provided which normally biases the pin 314 and therefore the slide 324 leftwardly as viewed in FIG. 23 so that the pin 308 will be held in the position shown. When the pin 314 is moved rightwardly from the position of FIG. 23, the arm 316 moves through a slight arc in the clockwise direction and the locking pin 308 enters the toggle link 244 as previously described.

Referring now to FIG. 22, the slide 312 is actuated by a yoke 330 pivoted at 331 to the main frame. The depending arms of this yoke are also pivoted to the slide 312 so that when the yoke is swung, the slide will be moved axially as viewed in FIG. 22. The yoke has a depending extension 334 in which there is provided a spring biased detent 336 for engagement with a thin cam plate 338 mounted in and extending above the surface of the main slide member 42. The leading end of cam plate 338 is inclined and of reduced height as shown at 342 in FIG. 22 and the rightwardly facing side of the detent 336 is similarly inclined.

At the beginning of the operating cycle, the main slide 42 will be disposed to the right of the detent 336 and as the slide moves leftwardly during its forward stroke the detent 336 will be moved upwardly against the biasing force of the spring 335 so that the yoke and the depending arm or extension 334 will not be swung and a stop is provided to prevent clockwise swinging of this arm. At the end of the forward stroke of the main slide, the rearward corner 340, of the cam plate 338 will have passed beyond the detent 336 which will now move downwardly to its normal position. During the initial portion of the return stroke of the main slide 42, the arm 334 and therefore the yoke 330 will be swung through a slight counterclockwise arc thereby moving the control slide 312 rightwardly a short distance. Rightward movement of this control slide in turn results in rightward movement of the pin 314 so that the slide member 324 will be moved out of engagement with the roll 322 and the lock pin 308 will be driven into the toggle link under the influence of the spring 320. At the end of the return stroke of the slide and the cam 338, the yoke will return to its normal position and the control slide 312 will be moved forwardly to its normal position (FIG. 23) so that the slide 324 will engage the roller 322 and cause the arm 316 to swing in a counterclockwise direction thereby resulting in a withdrawal in 308 from the toggle link.

Referring now to FIG. 11-14 and 19, the lower or movable cutter comprises a cutter blade 346 mounted on the end of a shank 350 adjacent to a channel shaped guard 348. Intermediate its end, this shank has a roller 354 mounted on its side and on its lower end, it has an integral rearwardly extending arm 358 on which there is provided another roller 356. The shank 350 is slidably mounted in a slot in the slide member 142 with the roller 356 disposed against the inclined edge 360 of a triangular opening in the slide 142. A spring 361 is provided which is anchored to a fixed portion of the frame and to the arm 358 of shank 350. This spring extends

under a roller 363 on the slide 142 and biases the shank to the position shown in FIG. 11. Adjacent to the roller 356 when the parts are in the position of FIG. 11, there is provided a one-way gate mechanism shown best in FIG. 19 which permits the roller 356 to move leftwardly during leftward movement of the slide plate 142 to the position of FIG. 12 but prevents the roller 356, and therefore, the shank 350 from moving rightwardly when slide plate 142 returns to its normal position as shown in FIG. 13. This one-way gate mechanism is contained in a housing or cage 365 which is pivotally mounted on the frame plate 28 by means of a pin 366. A slide member 364 is contained in the cage and has a vertically extending slot through which pivot pin 366 extends. The slide is biased upwardly by a spring 368 but can be cammed downwardly when the roller 356 moves against the inclined upper surface 367 of this slide. A guide bar 370 is fixed in the cage above the slide 364 and provides a rightwardly facing surface over which the roller moves. The cage is biased by a spring 374 to an upright position against a stop 375 but can swing through a counterclockwise arc to permit return of roller 356 to its initial position as will be explained below.

When the slide 142 moves leftwardly, from the position of FIG. 11 to the position of FIG. 12, the roller depresses the slide 364 and passes through the gate. It will be recalled that this leftward movement of the slide 142 takes place at the end of the forward stroke of the main slide and that during that initial part of the return stroke of the main slide, the slide 142 returns to its initial position, FIG. 13. During this movement of the slide 142, the roller 356 cannot move past the one-way gate and it is therefore compelled to move relatively up the surface 372 so that the shank 350 is moved obliquely upwardly in the slot in the slide 142 until it is adjacent to, and opposed to, the fixed cutter mechanism are shown in FIG. 13. When the parts are in the position of FIG. 13, the roller 354 which is mounted on the shank intermediate the ends thereof, it is in alignment with the contoured end 386 of a camming slide 384 which is described immediately below. It should be mentioned at this point, that the cutter is actuated by merely moving the camming slide leftwardly from the position of FIG. 13 thereby to drive the shank 350 obliquely upwardly and move the movable cutter 346 past the fixed cutter and sever the surplus strap material.

When the slide 384 moves leftwardly to drive the cutter obliquely upwardly as shown in FIG. 14, a horizontal extension 382 of a depending arm 380 mounted on the slide 384 engages the one-way gate housing and pivots it in a counterclockwise direction as viewed in FIG. 14. This pivotal movement of the one-way gate mechanism clears the way for the return of the shank 350 to its starting position under the influence of the spring 361 which is attached to the arm 358 of the shank. As clearly shown in FIG. 14, when the slide 384 reaches the leftward limit of its stroke, the roller 356 can move past the one-way gate and the movable cutter will be pulled downwardly.

FIG. 11 shows the movable cutter in its retracted or lowered position and FIG. 4 shows the positions of the parts after the movable cutter has been moved obliquely upwardly and past the tensioned strip portions of the tie to cut the tie. It will be noted in FIG. 14 that the roller 354 is in alignment with a groove 383 in

the slide 384 so that the shank of the movable cutter can move obliquely downwardly from the position of FIG. 14 to the position of FIG. 11, the groove 383 providing clearance for the roller 354. The movement of the parts from the positions of FIG. 11 to the positions of FIG. 14 takes place in two stages. In the first stage, the movable cutter is driven upwardly and into cutting engagement with the strap portion of the tie by straightening a toggle mechanism 388, 390 which drives the camming slide 384 leftwardly as will be described below. Cutting takes place during the final stages of straightening of this toggle mechanism so that an extremely high mechanical advantage is achieved for the actual cutting operation. The toggle mechanism 388, 390 is mounted on a short stroke slide 397 as will be described below and this short stroke slide is moved leftwardly for a very short distance during the second stage of this portion of the operating cycle. The leftward movement of the short stroke slide drives the slide 384 leftwardly for a short distance so that the roller 354 will be positioned in alignment with the slot to permit return of the cutter to its starting position.

This two stage operation is carried out in order to utilize the high mechanical advantages which is achieved at the instant of straightening the toggle mechanism for a the cutting of the tie, an operation which requires a relatively high force. The final increment of leftward movement of the slide 384 (during which the groove 383 is moved into alignment with the roller 354) does not require a high force and is effected by movement of the short stroke slide 397. The mechanism for straightening the toggle 388, 390 and thereafter moving the short stroke slide leftwardly are described below.

The toggle link 388 is pivotally connected to the slide 384 and is pivotally connected at 392 to the link 390 which in turn is pivotally connected to the short stroke slide. This toggle linkage is straightened by a bell crank 394 which is pivoted at 395 to the short stroke slide 397 and which has one arm 396 connected by a pin slot connection to the link 390. The other arm 398 of the bell crank 394 is pivotally connected to an additional bell crank 402 pivoted at 403 to the frame structure. The horizontally extending arm 404 of the bell crank 402 has a roller 406 on its end which bears against an inclined surface 408 of a cam 410. This cam is mounted on a slide 412 which is moved leftwardly from the position of FIG. 11 to the position of FIG. 14 in a manner described below. It will be apparent at this point that such leftward movement of slide 412 will cause counterclockwise movement of bell crank 402 about its pivotal axis 402, clockwise movement of bell crank 394 about its pivotal axis 395, and therefore, straightening of the toggle linkage 388, 390 to drive the camming slide 384 through the above-described first portion of its stroke.

The short stroke slide 397 is biased rightwardly by a spring as shown and is moved leftwardly only a very short distance and this movement must take place after the toggle linkage 388, 390 is straightened. In order to ensure that leftward movement of the cam 410 will initially bring out straightening of the toggle linkage 388, 390 rather than leftward movement of the slide 397, there is provided (FIGS. 29 and 30) an additional bell crank 438 on the pivot pin 403 which is behind the bell crank 402. The pivot pin 403 is mounted on in the frame and has one arm 446 which extends laterally into

an opening in the main frame and is pivoted to an extension 448 of the short stroke slide 397. The other arm 442 of bell crank 438 has a roller on its end which is normally against a surface 444 on the end of an arm of a block 440 secured to the slide 412. It will be apparent from FIG. 29 that bell crank 438 cannot pivot in a counterclockwise direction during initial movement of slide 412 because of the restraining influence of the surface 444 and it follows that the extension 448 of the short stroke slide 397 cannot move leftwardly. Therefore, during initial leftward movement of slide 412, the toggle link 388, 390 will be straightened and the short stroke slide 397 will be restrained against leftward movement. After the toggle linkage has been straightened, the bell crank 438 is permitted to swing through a small counterclockwise arc by virtue of the pocket 445 in the block 440 which is adjacent to the restraining surface 444.

The means for moving the slide 412 leftwardly from the position of FIG. 11 to the position of FIG. 14 will now be described.

A rod 414 is mounted in the righthand end of the slide 412 and extends rightwardly and into a bushing 416 mounted on the frame. A spring, which is compressed when the parts are in the position of FIG. 11, is interposed between the end of the bushing and the slide 412 and biases the slide leftwardly as viewed in FIG. 14. Slide 412 is restrained against leftward movement by a latch arm 422 pivotally mounted on a plate 424 which is secured to the frame, this latch arm having a depending tooth 426 which extends into a notch on the upper surface of the slide 412. The lefthand end of the pivoted latch arm 422 has a roller 428 thereon which bears against the surface of a cam 430 which is secured to the auxiliary slide 64, see FIG. 9A. An L-shaped stop 429 is also secured to the auxiliary slide 64 and bears against the upper edge of latch arm 422 to prevent the latch arm from swinging upwardly when the parts are in the positions of FIG. 11. A recess or notch 431 is provided in the upper edge of latch arm 422 so that upon rightward movement of the stop 429, limited upward or clockwise movement of the latch arm is permitted.

It will be apparent that when the auxiliary slide 64 moves rightwardly a short distance from its normal position as shown in FIGS. 9A-9C, the stop 429 and the cam 430 will move rightwardly and the latch arm 422 will swing through a slight clockwise arc by the cam 430. This clockwise movement of the latch arm causes the tooth 426 to move out of the notch in the slide 412 so that the slide is moved leftwardly under the influence of the spring 420. The leftward movement of slide 412 results in straightening of the toggle 388, 390 to cut the excess tie material.

It was mentioned previously that the auxiliary slide 64 remains stationary through most of the operating cycle as shown in FIGS. 9A-9C but that it moves rightwardly a short distance after the strap portion of the tie has been pulled taut. The manner of actuating the slide 64 to bring about this rightward movement will now be described.

A rod 432 (FIG. 9A) is mounted in the lefthand end of slide 64 and extends through a bushing 434 fixed in the main frame and extends leftwardly through a recess in the main frame. A bushing 439 is secured at the lefthand end of the rod and is slidably received in the recess. A nut 436 is threaded on the rod adjacent to the

sliding bushing 439, a spacer 437 is mounted on the rod adjacent to the nut 436, and a plurality of pairs of conical spring washers (Belleville washers) are mounted on the rod between the fixed bushing 434 and the spacer 437, the bases of each pair of washers being against each other so that an extremely stiff spring is provided between bushing 44 and spacer 437. The stiffness of this spring can be adjusted precisely by changing the position of the nut 436 to change the degree of compression in the washers.

The auxiliary slide 64 is restrained against movement during most of the operating cycle by virtue of the fact that it can move rightwardly from the position of FIG. 9A only if the spring system of the washers 438 is overcome and throughout most of the operating cycle, this condition does not obtain. As shown in FIG. 9A, the gear wheel 60 rotates in a counterclockwise direction during the forward stroke in which the slide 62 is moved leftwardly and since the slide 64 remains stationary, the stroke of the slide 62 is twice that of the piston rod 56. At the beginning of the return stroke, FIG. 9B, the piston moves rightwardly and since the slide 64 is stationary, the main slide 62 is driven rightwardly at twice the speed of the piston rod. After the tie has been drawn taut around the bundle (FIG. 9C) the tension in the tie increases to the point where the main slide 62 is more resistant to rightward movement than is the auxiliary slide 64. FIG. 9C shows the positions of the parts immediately before actuation of the movable cutter and indicates that the gear wheel 60 is now rotating in a counterclockwise direction. This situation obtains for a sort interval after the tension in the tie has reached a level such that its restraining influence on the main slide 62 is greater than the restraining influence of the spring system 438 on the auxiliary slide 64. The piston rod 56 continues to move rightwardly when equilibrium is reached and since the gear wheel is in engagement with the teeth of both slides 62, 64, it must change its direction of rotation as indicated in FIG. 9C. It thus drives the auxiliary slide 64 through a short stroke to the stop member 65 on the main frame and thereby causes the rightward movement of the cam 430 and the L-shaped stop member 429. This rightward movement of slide 64 actuates the movable cutter so that the restraining effect of the tensioned tie is removed from the main slide 62. The gear wheel again changes its direction of rotation and the main slide 62 is driven to the limit of its rightward stroke while the auxiliary slide 64 is returned to the position of FIG. 9A by the combined effects of the spring system of the washers 438 and the rotation of the gear wheel.

At the end of the return stroke of the piston it is necessary to return the slide 412 (FIG. 11) to its starting position so that it can be engaged by the latch arm 422 as shown in FIG. 11. This operation is carried out by a slide return bell crank 418 which is pivoted to the main frame and which has one arm 419 pivoted to a slidable bushing on the end of the rod 414, this arm extending through a slot in the fixed bushing 416 as shown in FIG. 11. The other arm 421 of bell crank 418 has a roller 423 on its end. This roller is located such that it is engaged by the camming surface 59 of yoke 58 at the end of the return stroke of the piston causing the bell crank to be swung through a clockwise arc whereby the rod 414 is driven rightwardly from the position of FIG. 14 to the position of FIG. 11. The latch arm 422 is resiliently biased by a spring to move into the notch in the

slide 412 so that the parts assume the positions of FIG. 11 at the end of the stroke of the piston.

In the foregoing description, it is stated that the strap portion of the tie is "cut" immediately after the parts reach the positions of FIG. 9C and the description is presented in this manner in the interest of faciliness. Strictly speaking, the tie is not completely cut by the cutters; it is probably notched and then, because of the tension in the tie by the main slide, it is torn until the excess of the strap portion is separated from the head portion. The material of which bundle ties are manufactured, nylon or other plastic, is usually highly notch sensitive which is to say that if it is nicked slightly, it can then be torn very easily. It follows that it is quite probable that after the movable cutter has moved against, and notched, the tie, the tension in the tie will cause the notch to be perpetrated as a tear immediately and at that instant, the gear wheel will reverse its direction of rotation.

It should be added that the auxiliary slide 64 will not necessarily move against the stop 65, that is, to the limit of its rightward stroke. If the tie is cut or torn before it reaches this stop, slide 64 will immediately return to its starting position.

The actual position of the main slide 42 at the time of cutting will depend upon the circumference of the bundle. If the bundle is very small, the main slide will be at the limit of its return stroke at the time of cutting. If the bundle has a large circumference, the slide 42 will have traveled through only a portion of its stroke at the time of cutting. In either event, the slide 64 will move against the fixed bushing 434 after cutting and the slide 64 will be stationary for the remainder of the cycle.

The final operation performed during the operating cycle immediately after the main slide reaches the limit of its return stroke is the feeding of a tie from the magazine onto the knife edge 32 of the plate 26. The magazine comprises a pair of parallel plates 450 in which the ties are stacked as shown so that the lowermost tie in the stack rests upon the surface of the main frame member. The feeding is carried out by a pair of feed fingers 452 which move laterally and toward the front plate frame member to move the lowermost tie onto the knife edge so that this tie will be in position for the next operating cycle. The two feed fingers are essentially identical so that a description of one will suffice for both. Each feed finger is pivoted to a lever 454 which extends rearwardly and is pivoted at 456 to a static portion of the frame. This spring 460 biases the lever in a counterclockwise direction to the normal position of FIG. 17. The levers 454 are swung through clockwise arcs during the initial portion of the forward stroke of the main slide by means of a cam plate 462 which have camming surface 464 in engagement with rollers 466 on the levers intermediate their ends. The cam plate has an ear 470 against which a spring 468 bears, the opposite end of this spring being disposed against an adjustable stop so that the amount of compression in the spring can be adjusted as required. When the parts are in their normal position, the camming plate 462 is held against leftward movement by a laterally extending ear 472 on the main slide which bears against a recess in the cam plate. When the main slide moves leftwardly from the position of FIG. 17, the cam plate 462 is moved leftwardly under the influence of the spring 468 and the levers 454 are swung through

clockwise arcs by the cams 464. The levers are held in this rotated position until the main slide returns to its normal position at which time the cam plate 462 is retracted and the lowermost tie is fed to the position of FIG. 17.

The operation of the disclosed embodiment is best understood from a study of the timing diagram. The tie itself is manipulated as illustrated in FIGS. 4-7 and the various components which perform the operations shown in FIGS. 4-7 are identified on the timing diagram and the time in the cycle at which they are actuated is indicated with reference to the forward and return strokes of the main slide 42.

Tie applicators in accordance with the invention have several outstanding advantages as compared with manually operated tie applying tools and as compared with previously proposed power tools for applying ties to bundles. The cycling time is extremely short, less than two seconds so that extremely high production rights are possible. Moreover, the disclosed form of apparatus is relatively compact and completely portable so that it can be manipulated by the operator with relative ease and this feature contributes to good production rates. The compactness is achieved in part because of the fact that a single piston-cylinder is used as a power source and all of the mechanism described above are actuated directly or indirectly by a piston-rod of this piston cylinder. Furthermore the piston-cylinder has a relatively short stroke since the arrangement of the slides 62, 64 permits the stroke of the main slide 62 to be twice that of the piston rod.

It will be understood that the timing diagram, FIGS. 31A, 31B assumes a specific bundle size since cutoff will take place after the tie has been tensioned and the completion of the tensioning operation depends upon the diameter of the bundle. An applicator in accordance with the invention is capable of applying ties to bundles having a wide range of diameters and cutoff can take place at any time during the return stroke of the master slide 42. The degree to which the tie is tightened at the time of cutoff can also be varied within limits by adjustment of the compressability of washers 438; in other words, by reducing the amount of force required to move the slide 64 against the biasing force of these spring washers.

Changes in constructions will occur to those skilled in the art and various apparently different modifications and embodiments may be made without departing from the scope of the invention. The matter set forth in the foregoing description and accompanying drawings is offered by way of illustration only.

What is claimed is:

1. Apparatus for applying a bundle tie to a bundle of conductors or the like, said bundle tie comprising an elongated relatively narrow strip having a leading end and a trailing end, an opening in said trailing end which is adapted to receive said leading end to permit intermediate portions of said tie to be drawn through said opening so that said tie can be drawn into embracing relationship with said bundle, said apparatus comprising:

frame means having a circular tie application zone, tie supporting means for supporting said tie in preparation for application to said bundle, said tie supporting means extending tangentially from one side of said tie application zone,

tie feeding means for feeding an individual tie, leading end first, along a predetermined path which extends to, and around, said application zone, said path having a first rectilinear portion which extends along said support means tangentially towards said zone, an arcuate portion which extends partially around said zone, and a second rectilinear portion which extends from said arcuate portion and has an intersection with said first rectilinear portion,

a first reciprocable slide, said feeding means comprising pushing means on said first slide for pushing said trailing end of said tie thereby to advance said tie along said first rectilinear portion of said path and along said arcuate portion to said intersection, tie tightening means comprising means for grasping said leading end and pulling said leading end away from said zone,

cut off means for cutting said tie adjacent to said opening after said tie has been drawn into snugly embracing relationship with said bundle,

a reciprocable actuator for reciprocating said slide, first rack means on said slide and a gear wheel on said actuator, said gear wheel meshing with said first rack means, said apparatus having second rack means extending parallel to said first rack means, said gear wheel meshing with said second rack means, said second rack means being resistant to linear movement whereby, said gear wheel is rotated during linear movement of said actuator and said first rack means is moved in the direction of movement of said actuator at a velocity which is greater than the velocity of said actuator whereby,

upon actuation of said actuator when a bundle is positioned in said zone, said tie will be fed along said path and its leading end will be fed through said opening at said intersection, and thereafter said leading end will be grasped by said tightening means and pulled away from said zone until said tie snugly embraces said bundle and said tie will thereafter be cut by said cut off means.

2. Apparatus as set forth in claim 1 said feeding means further comprising means for pushing a portion of said tie which extends along said second rectilinear portion of said path towards said application zone while said trailing end is being pushed along said first rectilinear portion of said path whereby an intermediate portion of said tie is forced to move through said opening while said trailing end is moved towards said application zone.

3. Apparatus as set forth in claim 2, said apparatus having means for moving said trailing end of said path towards said tie application zone after said trailing end has substantially reached the end of said first rectilinear portion of said path whereby said leading end is pulled by said tightening means radially with respect to said bundle.

4. Apparatus as set forth in claim 3, said slide having head means thereon, said pushing means comprising surface portions of said head means, said tightening means comprising means in said head means for grasping and clamping said leading end of said tie.

5. Apparatus as set forth in claim 4, said apparatus having a magazine for holding a plurality of ties, and having means for dispensing a tie from said magazine and positioning said tie on said first rectilinear portion of said path.

6. Apparatus as set forth in claim 1, said actuator comprising a piston-cylinder.

7. Apparatus as set forth in claim 1, said second rack means being linearly movable upon application of a predetermined force thereto whereby upon development of a predetermined tension in said tie, said first rack means is restrained against movement and said second rack means is moved, said cut off means being responsive to movement of said second rack means to cut said tie.

8. Apparatus for applying a bundle tie to a bundle of conductors or the like, said bundle tie comprising an elongated relatively narrow strip having a leading end and a trailing end, an opening in said trailing end which is adapted to receive said leading end to permit intermediate portions of said tie to be drawn through said opening so that said tie can be drawn into embracing relationship with said bundle, said apparatus comprising:

frame means having a circular tie application zone, tie feeding means for feeding an individual tie, leading end first, along a predetermined feed path which extends to, and around, said application zone,

a first reciprocable slide, said feeding means comprising pushing means on said first slide for pushing said trailing end of said tie along said feed path upon movement of said slide towards said application zone,

tie tightening means comprising gripping means on said first slide for gripping said leading end and pulling said leading end away from said zone upon movement of said slide away from said zone,

cut off means for cutting said tie adjacent to said opening after said tie has been drawn into snugly embracing relationship with said bundle,

actuating means for said first slide and said cut-off means, said actuating means comprising first and second rack bars, said first rack bar being secured to said first slide, said second rack bar being spaced from, and extending parallel to, said first rack bar, a gear wheel meshing with both said first and second rack bars, resilient means normally preventing movement of said second rack bar away from said zone and positive stop means preventing movement of said second rack bar towards said zone, power means for moving said gear wheel towards and away from said zone and,

means responsive to movement of said second rack bar away from said zone for actuating said cut off means whereby,

upon movement of said gear wheel towards said zone, said first rack bar and said first slide are moved towards said zone thereby to feed said tie into surrounding relationship to a bundle in said zone until the leading end of said tie is fed through said opening and is gripped in said gripping means, and upon movement of said gear wheel away from said zone, said first rack bar and said first slide are moved away from said zone thereby to tighten said tie onto said bundle until said first slide and said first rack bar are restrained against further movement, and said second rack bar is thereafter moved away from said zone by said gear wheel thereby to actuate said cut off means.

9. Apparatus as set forth in claim 8, said power means comprising a piston-cylinder.

10. Apparatus as set forth in claim 8, said predetermined feed having a first rectilinear portion which extends towards said zone, an arcuate portion which extends partially around said zone, and a second rectilinear portion which extends from said arcuate portion and has an intersection with said first rectilinear portion, said apparatus having means responsive to movement of said first slide for pushing a portion of said tie which extends along said second rectilinear portion towards said application zone while said trailing end is being pushed along said first rectilinear portion of said

path whereby an intermediate portion of said tie is forced to move through said opening while said trailing end is moved towards said application zone.

11. Apparatus as set forth in claim 10 having means for moving said trailing end of said tie towards said application zone after said trailing end has substantially reached the end of said first rectilinear portion of said path whereby said leading end is pulled by said tightening means radially with respect to said bundle.
